UNITED STATES PATENT OFFICE.

CURTIS M. JENNINGS, OF ST. LOUIS, MISSOURI.

CAR-ROOF.

SPECIFICATION forming part of Letters Patent No. 696,976, dated April 8, 1902.

Application filed December 23, 1901. Serial No. 87,004. (No model.)

To all whom it may concern:

Be it known that I, CURTIS M. JENNINGS, a citizen of the United States, residing at St. Louis, in the State of Missouri, have invented 5 a new and useful Improvement in Car-Roofs, of which the following is a specification.

My invention relates to a metallic car-roof for freight-cars, and has for its object to provide a rigid and durable car-roof of simple 10 construction without the use of the upper purlins, upper ridge-pole, roof-boards, and fascias ordinarily appertaining to this class of roof.

The invention consists in features of novelty, as hereinafter described and claimed, 15 reference being had to the accompanying drawings, forming part of this specification, whereon—

Figure 1 is a top plan of my improved metallic car-roof broken away; Fig. 2, a vertical transverse section, to enlarged scale, through the roof, broken away on line 2 2 in Fig. 1; Fig. 3, a cross-section, to enlarged scale, through one of the carlines and adjacent roof-sheets, broken away on line 3 3 in Figs. 1 and 2; and Fig. 4, an end view of the carline and adjacent roof-sheets at their junction to the side of the car, seen in side elevation broken away.

Like letters and numerals of reference denote like parts in all the figures.

In my improved metallic car-roof, *a* represents the carlines; *b*, the roof-sheets; *c*, the lower purlins, and *c'* a middle tie-plate corresponding to the purlins *c* and substituted for the ordinary ridge-pole of a car-roof. Each car-line *a* is composed of iron, steel, or other suitable material and is preferably channel-shaped in cross-section, having the bottom flat 30 portion or base *1* and the two upwardly-projecting side flanges *2*, which are directed outward at the top *3* and formed thereat with a depending flange *4*, which is opposite to and parallel, or thereabout, with the side flanges *2* at a suitable distance therefrom. The roof-sheets *b*, which are preferably flat, extend between the carlines *a* and are formed, respectively, at each side with an upwardly-projecting flange 45 *5*, which is adapted to engage between the side flange *2* and the outer depending flange *4* of the corresponding carline *a*, adjacent thereto, the flanges *2* and *4*, with their top

connecting portions *3*, forming housings to the flanges *5* of the roof-sheets *b*, and thereby excluding rain and dust from the car.

The carlines *a* and roof-sheets *b*, which span and overhang the sides *d* of the car, are of equal length and preferably in one piece, respectively, from end to end, the sides *d* of the car having outwardly-projecting top flanges 60 *6* extending their entire length, to which the overhanging end portions of the carlines *a* and roof-sheets *b* are firmly secured by rivets *7*, which in the case of the carlines *a* pass through the base *1* and flanges *6*, as shown. 65 To the inner face of each side *d* at the top is preferably fixed an "angle-plate" *e*, having its upper projecting leg *8* flush with the flange *6*, and to this leg *8* the carlines *a* and roof-sheets *b* are fixed by rivets *9*. Each end of 70 the car (not shown) is also preferably provided with an overhanging top flange and inside angle-plate similar to the flange *6* and plate *e* of the sides *d*.

The lower purlins *c* and middle tie-plate *c'* 75 may be of flat bar or other suitably-shaped irons and are fixed to the carlines *a* and roof-sheets *b* on their under side by rivets *10*, as shown.

The running-board *f* is supported on bearings *g*, made of pressed steel, malleable cast-iron, or other suitable material in any desired form and fixed at the base to the roof-sheets *b* at each side of the roof-ridge by rivets *11* or otherwise, as found most suitable.

By the special form of carline *a* above described the joint-strips or roof-rafters and the deep wooden carlines or rafters within the car, as also the upper purlins and upper ridge-pole and fascias, are dispensed with and the 90 construction of the roof greatly simplified; also, by making the carlines *a* in one piece, respectively, from side to side of the car and attaching them at the eaves to the overhanging flanges *6* and inside plates *e* of the sides *d* of the car the roof is rendered more rigid and durable and adds greater strength to the 95 car than by the ordinary construction.

What I claim as my invention, and desire to secure by Letters Patent, is—

1. In a car-roof, the combination with the sides of the car having respectively an outwardly-projecting top flange, of a carline made in one piece spanning the said sides, the said

carline having a flat base bearing upon the said flanges, and having two upwardly-projecting side flanges directed outward at the top and formed thereat respectively with a depending flange, a roof-sheet having a side flange adapted to engage between the said side flange and depending flange of the carline, and means for fixing the carline and roof-sheet to the said top flanges of the car, substantially as described.

2. In a car-roof, the combination with the sides of the car having respectively an inside top angle-plate, of a carline made in one piece spanning the said sides, the said carline having a flat base bearing upon the said plate, and having two upwardly-projecting side

flanges directed outward at the top and formed thereat respectively with a depending flange, a roof-sheet having a side flange adapted to engage between the said side flange and depending flange of the carline, and means for fixing the carline and roof-sheet to the said top plate of the car, substantially as described.

In testimony whereof I have signed my name to this specification in the presence of two subscribing witnesses.

CURTIS M. JENNINGS.
